United States Patent Office.

JONATHAN F. SHOEMAKER, OF VAN WERT COUNTY, OHIO.

Letters Patent No. 64,374, dated April 30, 1867.

PHOTOGRAPHIC PRINTING FRAME.

The Schedule referred to in these Letters Patent and making part of the same.

TO ALL WHOM IT MAY CONCERN:

Be it known that I, JONATHAN F. SHOEMAKER, of the county of Van Wert, and State of Ohio, have invented a new and improved mode of Printing Photographs; and I do hereby declare that the following is a full and exact description thereof, reference being had to the accompanying drawings, and the letters and figures of reference marked thereon.

The nature of my invention consists in enabling the photographer to print and place on the same surface as many groups or figures as he may desire from different negatives.

To enable others skilled in the art to make and use my invention, I will proceed to describe its construction and operation.

Figure *a* represents the printing board partially open, with its folding back, the several folds numbered 1, 2, 3, and 4. The first fold (No. 1,) holds the edges of the negatives firmly for all the openings that may be across the face-board *a* under the second fold, 2. The fold 2 will hold the negatives for the openings in face-board under No. 3, and fold 3 will hold them for No. 4, &c., for any sized frame and any number of pictures. While No. 1 holds the first row of negatives, the folding back can be turned down to No. 1, so as to inspect the printing in progress through the openings under No. 2, and as each fold holds the negatives for printing through the openings under the next fold above, the folding back will drop down from off the prints, leaving the negatives perfectly firm, so that the progress of the printing may be inspected at any moment with ease, by the dropping of the folding back.

Figure B presents the face of the printing-board. The rays of light directed to the face of the board are kept from the paper or other material by means of small cloth coverings, *b b b*, over the openings, (or coverings of any material which will exclude the rays of light,) which are moved or opened and closed at pleasure. As the printing progresses each row of prints is closed by means of back and face coverings, and these prints are not exposed to the light while examining the process of printing the next row above. In the last row of pictures there is, of course, but one fold to turn down to inspect the printing. Each print is checked when done, by closing the face opening above it.

What I claim as my invention, and desire to secure by Letters Patent, is—

The "folding-back photographic printing frame," substantially as herein described.
